CLAIM

The ornamental design for a control panel for an access control system, as shown and described.

DESCRIPTION

FIG. 1 is a top-front-right isometric view of a control panel for an access control system (e.g., a physical access control system (PACS)), showing my new design;

FIG. 2 is a bottom-front-right isometric view of the control panel of FIG. 1;

FIG. 3 is a top-rear-left isometric view of the control panel of FIG. 1;

FIG. 4 is a bottom-rear-left isometric view of the control panel of FIG. 1;

FIG. 5 is a front view of the control panel of FIG. 1;

FIG. 6 is a rear view of the control panel of FIG. 1;

FIG. 7 is a left view of the control panel of FIG. 1;

FIG. 8 is a right view of the control panel of FIG. 1;

FIG. 9 is a top view of the control panel of FIG. 1; and,

FIG. 10 is a bottom view of the control panel of FIG. 1. The broken lines of FIGS. 1 to 6 and 10 are provided for purposes of illustrating portions that form no part of the claimed design of the present application.
